FLUORESCENT LIGHTING LOUVER

Stanley Deutsch, 27 Jordan Road,
Hastings on Hudson, N.Y. 10706

Filed Aug. 12, 1968, Ser. No. 13,103

Term of patent 14 years

Int. Cl. D26—99

U.S. Cl. D48—16

FIG. 1

FIG. 2

FIG. 3

FIG. 4

FIG. 1 is a bottom perspective view of a fluorescent lighting louver unit embodying my new design which may be infinitely repeated both lengthwise and widthwise as indicated by the broken lines.

FIG. 2 is a top plan view thereof.

FIG. 3 is a side view thereof.

FIG. 4 is a bottom perspective view of a modified form of a fluorescent lighting louver unit which may be infinitely repeated both lengthwise and widthwise as indicated by the broken lines.

I claim:

The ornamental design for a fluorescent lighting louver, as shown and described.
